UNITED STATES PATENT OFFICE.

FELIX GRZESZKIEWICZ, OF MILWAUKEE, WISCONSIN.

IRONING BOARD.

Application filed September 29, 1923. Serial No. 665,723.

Ironing boards are of two general types, one being supported upon tables, or two spaced supports, and when not in use is stood in a corner or a suitable closet, and the 5 other concealed within a cabinet set in the wall and adapted to be swung out for use. The first mentioned type is objectionable in that when mounted on two spaced supports for use it is apt to become disengaged and is 10 more or less in the way when stood in a corner or closet. The last mentioned type is objectionable in that the ironing board cannot be made of the desired width as the cabinet must be fitted between the studdings and 15 furthermore is expensive and cannot be placed in homes except at the time of their construction without tearing out the wall.

With the above and other objections to the types of ironing boards now generally 20 employed in mind, this invention has for one of its objects to provide a structure of the character described which may be made in any desired size and which can be readily placed in homes either during their construction or after their completion.

It is another object of this invention to provide a device of the character described in which an improved type of supporting leg is provided for the free end of the ironing board when in use, whereby the same is 30 rigidly supported without interference with the article being ironed.

Another object of this invention resides in the provision of an ironing board of the 35 character described in which the support therefor has an opening therein of a shape to receive the board with its outer face flush with the support when not in use.

Another object of this invention resides in 40 the provision of a device of the character described in which the support and ironing board are constructed from a single plank of wood to thus effect economy in labor and material in the course of its manufacture.

45 A further object of this invention resides in the provision of a supporting leg constructed of two parts pivotally connected together and constructed from a single length of material to thus effect an economy in manufacture.

50 And a still further object of this invention resides in the provision of a device of the character described which is simple in con-

struction, strong and durable, and which can be produced at a comparatively low cost. 55

With the above and other objects in view which will appear as the description proceeds, my invention resides in the novel construction, combination and arrangement of parts substantially as hereinafter described 60 and more particularly defined in the appended claims, it being understood that such changes in the precise embodiment of the herein disclosed invention may be made as come within the scope of the claims. 65

In the accompanying drawings, I have illustrated one complete example of the physical embodiment of my invention constructed according to the best mode I have so far devised for the practical application of 70 the principles thereof, and in which:

Figure 1 is a perspective view illustrating the ironing board embodying this invention;

Figure 2 is a longitudinal sectional view taken through Figure 1 on the plane of the 75 line 2—2;

Figure 3 is a view looking at the rear of the device on the plane of the line 3—3 of Figure 2, a portion of the support and the board being broken away and in section to 80 illustrate the means for securing the board in its inoperative or closed position;

Figure 4 is an enlarged fragmentary detail view, partly in section and partly in elevation, taken through Figure 3 on the plane 85 of the line 4—4 and illustrating the hinged connection between the board and its supporting leg;

Figure 5 is a side view of the ironing board illustrating the same in extended position ready for use, but a fragment of the support being illustrated, and 90

Figure 6 is a view similar to Figure 5 of a slightly modified form of supporting leg.

Referring now more particularly to the 95 accompanying drawings, in which like numerals designate like parts throughout the several views, the numeral 5 designates a plank of wood or other material having an opening 6 cut therein of a shape to receive an ironing board 7. The board 7 is formed from the same plank forming the support 5 during the cutting of the opening 6 therein, the cut being preferably taken by starting from points 8 and 8' to points 9 and 9', 100 respectively, and then providing the trans-

verse cuts to produce the pieces 10 and 11 which are afterward glued or otherwise secured in place to connect the sides of the support. In this manner of forming the 5 support 5 and board 7, considerable material and labor is saved and in addition proper fitting of the board 7 in the opening 6 is assured.

The support 5 is preferably provided with 10 side flange pieces 12 adapted to be secured to the wall 13 in the most convenient position by fastenings 14. The side pieces 12 space the support from the wall 13 to provide a recess or compartment 15 in which 15 the foldable leg, to be later described, for supporting the board when in extended or horizontal position, is concealed when the board is in its position illustrated in Figure 1 with its outer face flush with the upper 20 face of the support 5.

The lower or inner end of the board 7 is connected with the support at the end of recess 6 formed by piece 10 by hinges or other means 16 and the outer end thereof has 25 one member 17 of a two-part leg structure pivotally connected therewith by a hinge 18 including two end links 19 and 20 pivotally connected by an intermediate link 21, see Figure 4. The link 19 is secured to the outer 30 or free end of the board and the link 20 is secured to the outer end of the member 17, the link 21 being folded over the link 19 when the board is in folded position, see Figure 4, and over the link 20 when the board 35 is in open or extended position, as illustrated in Figures 5 and 6.

The member 17 has a central, longitudinally extending slot or recess 22 in which the leg proper 23 of the other leg member 24 is 40 adapted to be folded when the board is secured in the recess 6. The member 24 is pivotally connected with member 17 by a pin 25, as illustrated in Figure 3, and that portion of member 24 extended beyond the leg 45 23 is of a width substantially equal to that of member 17, providing shoulders 26, for the purpose herinafter described. The members 17 and 24 are cut from a single length of wood, the formation of the leg 23 producing recess 22, thus providing an economy in labor and material and insuring the fitting of the leg 23 in the recess 22 when the leg structure is folded.

The upper end of the member 24 is preferably provided with a transverse piece or head 27 thereby forming a substantially T-shaped supporting member, the head of which engages the under surface of the board when 50 in extended position to insure a firm support throughout substantially its entire width. When in extended position, the parts take the positions illustrated in Figures 5 and 6, head 27 engaging the under surface of the board and the lower end of leg 23 being positioned rearwardly of an imaginary line 60

drawn perpendicularly through pin 25, the shoulders 26 abutting the top face of the adjacent portion of member 17, and the head 27 abutting a stop 28 carried by the board. If desired, the stop 28 may be the manufacturer's name plate. With this construction the ironing board is firmly supported and the shoulders 26 and stop 28 provide a rigid brace for the member 24.

When it is desired to put the board away, 75 member 17 is swung outwardly and then inwardly on its pivot, member 24 folding therein of its own accord by reason of its end 23 being the heavier. The board 7 is then swung upwardly into the opening 6 and 80 readily releasably secured therein by a spring pressed ball or plunger 29 engaging a keeper 30 carried by the board side. It will also be apparent that in moving the board to open position, either the name plate 28 or a knob 85 90 or handle 31 may be used to open the same against the spring pressed plunger 29, and as the board approaches its normal horizontal position the leg structure is swung on the hinge 18. As the leg structure is swung toward operative position on hinge 18, it will, of its own accord, assume normal position by reason of the leg end 23 being heavier than the opposite end, as will be readily obvious.

As illustrated in Figures 5 and 6, the leg 95 23 may engage the floor rearwardly a slight distance beyond a line drawn perpendicularly through pivot 25 or else may extend over to engage the base of the wall as illustrated in Figure 6, the only change in construction being the relative sizes of the members 17 and 24.

What I claim as my invention is:

1. A device of the character described, comprising an ironing board, means pivotally mounting one end thereof, and a leg structure for supporting the other end of the board in substantially horizontal position and including a member hingedly connected therewith, said member being slotted throughout the major portion of its length to its outer, free end, a second member of substantially T-shape and means medially pivotally mounting said second member in said slot adjacent the outer end thereof, the leg of said T-shaped member being foldable into the slot of the other member when not in use, said leg members being nested and folded against the upper face of the board when not in use and being opened with the transverse end of the T-shaped member engaging the under surface of the board and its other end engaging the floor when in use.

2. A device of the class described including a wall receptacle having an opening therein, an ironing board having an upper and an under surface, said board being pivotally connected with the receptacle and adapted to close the same when moved to inoperative position, a supporting leg structure 125 130

composed of two pivotally connected parts, means pivotally connecting one leg part with the end portion of the board, the second leg part being engageable with the intermediate portion of the under surface of the board for supporting the same when in use, said leg structure being foldable and swing-

able on the pivotal connection with the board to lie flush against the upper surface of the board when not in use and being concealed within the receptacle by the board when the receptacle is closed. 10

In testimony whereof I affix my signature.
FELIX GRZESZKIEWICZ.
